UNITED STATES PATENT OFFICE

107,518

DESIGN FOR A DESK MEMORANDUM SHEET HOLDER

Oscar F. Holmgren, White Plains, N. Y., and William B. Petzold, Providence, R. I., assignors to Autopoint Company, Chicago, Ill., a corporation of Illinois

Application September 24, 1937, Serial No. 71,772

Term of patent 14 years

To all whom it may concern:

Be it known that we, Oscar F. Holmgren and William B. Petzold, citizens of the United States, residing at White Plains, in the county of Westchester and State of New York, and Providence, in the county of Providence and State of Rhode Island, respectively, have invented a new, original, and ornamental Design for Desk Memorandum Sheet Holder, of which the following is a specification, reference being had to the accompanying drawing, forming a part thereof.

In the drawing:

Fig. 1 is a top plan view of a desk memorandum sheet holder showing our new design.

Fig. 2 is a side elevation of the holder shown in Fig. 1.

Fig. 3 is a bottom plan view of the same.

Fig. 4 is an end elevation looking toward the left-hand end of Fig. 1.

Fig. 5 is an end elevation looking toward the right-hand end of Fig. 1.

We claim:

The ornamental design for a desk memorandum sheet holder substantially as shown.

OSCAR F. HOLMGREN.
WILLIAM B. PETZOLD.
